CLAIM

The ornamental design for a portable mortorized manicuring apparatus, as shown and described.

DESCRIPTION

FIG. 1 is a left side elevational view of the portable mortorized manicuring apparatus of the present invention; FIG. 2 is a right side elevational view of the portable mortorized manicuring apparatus of FIG. 1; FIG. 3 is a front elevational view of the portable mortorized manicuring apparatus of FIG. 1; FIG. 4 is a back elevational view of the portable mortorized manicuring apparatus of FIG. 1; FIG. 5 is a top plan view of the portable mortorized manicuring apparatus of FIG. 1; and, FIG. 6 is a bottom plan view of the portable mortorized manicuring apparatus of FIG. 1. The broken line showing of the cord is for illustrative purposes only and forms no part of the claimed design.
